UNITED STATES PATENT OFFICE.

OLIVER LINDSAY AND ROBT. F. STREAN, OF WASHINGTON, PENNSYLVANIA.

GRAIN-FAN.

Specification of Letters Patent No. 26,273, dated November 29, 1859.

To all whom it may concern:

Be it known that we, OLIVER LINDSAY and ROBERT F. STREAN, of Washington, in the county of Washington and State of Pennsylvania, have invented a new and useful Improvement on the Grain-Fan now in Common Use; and we do hereby declare that the following is a full and exact description of the construction and operation of the same, reference being had to the annexed drawings, making a part of this specification, in which—

Figure 1 is a perspective view of the entire fan as arranged for chaffing; Fig. 2 is a perspective view of the shoe as arranged for separating cheat, smut, &c., in second cleaning.

In Fig. 1, A, is a division board hung on a pivot at *d* and moving between the points *a b*; thus dividing the wind thrown off by the fan into two currents, the under current being greater or less as the division board A is elevated or depressed. B is an inclined plane permanently fastened in the shoe in a line with the division board A and forming as it were, a continuation of the same. C is the chaffing riddle used in first cleaning. D is the hopper bottom and fastened to the shoe. E is the back board of the hopper and fitting down close and smooth on the hopper bottom. F is the lower and fine riddle operated upon by the wind passing below the division board A. G is the screen board hung on or hinged to the shoe at *e* and resting on a roller at *I*. H is a roller under the back end of the hopper bottom D.

In Fig. 2 the parts are the same as described in Fig. 1 except that the Venetian riddle C is removed and the cheat and smut board K is placed in the shoe from the point *h* at an inclination toward the out end of the inclined plane B.

To enable others skilled in machinery to make and use our invention, we will proceed to describe its construction and operation.

We construct our fans, frame and out side shell after the usual form of the common grain fan. The shoe is made to fit close to the inside and hung at the points *f g* and the back end rests on the roller H; the vibration being lengthwise of the fan. We then hang the screen board to the shoe at *e* and rest the other end upon the roller I, thus giving one and the same motion to the shoe hopper bottom and screen. We then place the in-

clined plane B permanently in the shoe, as shown in the annexed drawings, and in a line with the division board A, for the purpose of compelling all the wind, which passes above the division board A, to pass up through the chaffing riddle C thus using all the wind directly upon the riddle, and also for the purpose of carrying the grain to the back end of the lower riddle F to subject it to the action of the current of wind which passes under the division board A, and also for the further purpose which will be described in Fig. 2.

The division board A is pivoted at the point *d* immediately in the rear of the lower riddle F, and extended in an oblique direction to the line described by the perimeter of the fan at the point *a* for the purpose of dividing the wind into two currents, the one passing above the division board A and the inclined plane B up through the chaffing riddle C, the other beneath the division board A up through the wheat riddle F and out beneath the inclined plane B, thus by means of the division board A and the inclined plane B the grain is subjected to two processes and two currents of wind while passing once through the fan. The division board A is regulated by a thumb screw, as shown at *k*, and may be set at any point between the points *a b*, for the purpose of passing a greater or less portion of wind above or below the division board A as the circumstances of the grain may require. The riddle F is made as any other common wire riddle.

The chaffing riddle C may be constructed as any of the common wire riddles but we have made it in the form of a Venetian as shown in the annexed drawings, Fig. 1, the slats being made of wood or iron about $\frac{1}{4}$ of an inch wide and $\frac{1}{16}$ thick and placed about 1 inch apart, wire being drawn at right angles to the slots about 1 inch apart and fastened to them. The back end of the hopper bottom D is passed out beneath the hopper board E and rests upon the roller H. The hopper board E is made to fit down close and smooth to the hopper bottom D, and we then give the same vibration to the hopper bottom D as to the shoe and make it to pass back and forth beneath hopper board E for the purpose of pushing the grain forward in the hopper and making it a self feeder.

Fig. 2 represents the shoe as arranged for

passing grain through the second time. The chaffing riddle C is removed and the cheat and smut board K is placed in an oblique direction toward the inclined plane B, for 5 the purpose of confining the wind so as to expose the grain to a strong current as it passes down the inclined plane B the wind carrying substances lighter than the grain up the plane, while the grain, its weight 10 being greater than the force of the wind, passes down and falls on the lower riddle F where it is again exposed to the current of wind passing beneath the division board A and the inclined plane B.

15 The first process is simply this; the grain in the chaff is thrown into the hopper and by the action of the bottom D and the back E it is pushed forward upon the riddle C and being exposed to the current above the 20 division board A and the inclined plane B the chaff is carried off; by means of the inclined plane B the grain is thrown back upon the in end of the lower riddle F and exposed to the current which passes beneath the division board A and the inclined plane B; it then passes down the screen board G, in which is inserted a large screen, 25 to the place of general delivery.

The second process is similar to the first,

except that the chaffing riddle C is removed 30 and the cheat and smut board K is placed as shown in Fig. 2 and the grain exposed to a strong current upon the inclined plane B.

We do not claim broadly and irrespective of construction and arrangement a grain 35 fan, for such devices have been in common use and arranged in various ways. Neither do we claim, simply and independent of each other, the division board A; the inclined plane B; the screen board G; or the 40 riddles C and F, for these, or their equivalents, are in common use: but

We claim—

The combination of division board A with the inclined plane B, the screen board G, 45 and the riddles C and F when the same are united in the peculiar manner above described, and arranged to operate in the relation to each other and to the currents of wind thrown off by the fan, as fully shown 50 in Fig. 1 substantially as and for the purpose set forth and specified.

OLIVER LINDSAY.
ROBT. F. STREAN.
